UNITED STATES PATENT OFFICE

2,547,170

CENTER SELVEDGE FORMING DEVICE

Jaime Picanol, Ypres, Belgium

Application September 30, 1947, Serial No. 777,058
In Belgium November 27, 1943Section 1, Public Law 690, August 8, 1946
Patent expires November 27, 1963

4 Claims. (Cl. 139—54)

1

The invention relates to a new device for the formation of special selvedge or split in the middle of the fabrics when weaving in one operation a plurality of fabrics of a width which is less than the reedspace of the loom. It is known that several fabrics of different width can be woven on one same loom when between the fabrics, woven next to each other, a strip without warp yarn has been provided. Later on these fabrics are separated by cutting off the entire piece along the axis of said parts without warp yarn. It is however necessary to provide along the sides thus cut off, a selvedge or split capable to prevent the ravelling of the fabric, which at these places is unprovided with the normal selvedge which generally exists along the external sides of the fabrics.

Certain devices have already been suggested for the production of such selvedges, which make use of a fixed rod, cut out in such a way that it represents two fixed needles, each needle having on its end an eyelet, this fixed rod and those needles cooperating with a movable rod provided with inclined slits ending on an eyelet, in such a manner that the threads when passing through said slits, are capable of being displaced transversely, so as to form a special twilling which will form the pseudo-selvedge or splits. The latter, as produced by this device, generally has the form of a combination of a straight warp yarn with a warp-yarn interwoven between said straight warp-yarn and the successive picks.

The present invention concerns a new device permitting to realize the selvedges or centre-selvedge in a systematic way, providing at the same time a greater resistance and the possibility of being better adapted to the nature of the fabrics due to the fact that the interweaving of a warp-yarn can be effected along two straight warp yarns and at wish, at each pick, at every two picks, every four picks, etc.

The device manufactured in accordance with the present invention is characterized by a combination of three rods which are placed in juxtaposition, whereby all three of them carry out a straight, alternative movement in a vertical plane, parallel to the plane of the card.

In the appended drawings:

Figure 1 is a diagram illustrating the weaving of the fabric;

Figures 2 to 5 are diagrammatic perspective views showing the three movable rods separate from each other, and in four different positions;

Figure 6 is a diagrammatic elevational view of the weaving loom, showing the position of the device;

2

Figure 7 is a lateral view of the loom of Figure 6;

Figures 8, 9 and 10 are diagrams illustrating different center selvedges.

Figure 1 shows that it is possible to provide the centre selvedge, while maintaining straightened the two threads of the chain *a*—*b* and interweaving a third thread of the chain *c*, respectively between the first two and the picks or weftyarn.

The movements after the execution of the weft *d* show that the chain *a* must be kept elevated, the chain *b* lowered, whilst the chain *c* must be lowered, thus covering the first two transversely. This transverse covering is obtained in accordance with the device of the invention, by the displacement of the two chainyarns *a*, *b* with a small transverse movement, the third chainyarn *c* being always displaced in the same vertical plane. From then on, the chainyarns *b*, *c* are lowered and the chainyarn *a* is raised, and this position is maintained during the formation of the wanted quantity of picks, in this case three. Immediately afterwards the chainyarns *a*, *b* are displaced transversely, but in reverse sense, the chainyarn *b* being raised and the chainyarn *a* being lowered; in these new positions the same quantity of picks is formed and these successive movements are thus continually repeated. It is sufficient to provide in due time the lowering, raising and the standstill of the chainyarns which are to form the centre-selvedge, two of these yarns receiving periodically a little transverse movement, once in one direction, once in the other, the first chainyarn *a* being passed through the eyelet of a needle, which is carrying out an alternative straight movement. The result is that this needle places alternately its chain yarn to the left or the right of the first two. The interweaving, forming the centre-selvedge is thus realised.

The device has been conceived so that it can realise at the same time two selvedges, respectively, for the adjacent sides of the two fabrics which are being woven simultaneously.

According to the Figures 2, 3, 4 and 5 the device has three rods, 1, 2 and 3 placed one behind the other and capable of carrying out an alternative vertical movement.

The first rod 1 has an opening 4 cut out in such a way that it presents two eye-needles 5, 6 of which each point is directed downwards and has an eyelet respectively 7, 8.

Above the needles a transverse slit 9 has been provided. Each needle receives a warp-yarn C,

which goes through the eyelets, respectively 7, 8, comes again before the needle and then across the transverse slit 9. The second rod 2 has two slits 10, 11 situated at one of the sides of the rod, having a double curve and disposed towards the other longitudinal side of the rod. In this second part these slits are doubled by two other straight slits 12, 13. At the beginning of the first curve of the slits 10, 11, the rod 2 is also crossed by two small oblong eyelets 14, 15. The third rod 3 has the same slits and the same eyelets as the rod 2 but the disposition is reversed, namely, the slits 10', 11', are firstly extending along the longitudinal side of the rod opposite the longitudinal side of the rod 2 bordered by the slits 10, 11. These slits 10', 11' also have at the level of the slits 10, 11 a double curve, which is displacing them towards the opposite longitudinal side. This second part of the slits 10, 11' is doubled by the straight slits 12', 13'. The eyelets 14', 15' are disposed at the beginning of the double curve of the slits 10', 11'.

The warp-yarns 'C extend through the transverse opening 9 of the first rod 1, and through the straight slits 12, 12' and 13, 13' of the rods 2 and 3. The warp-yarns 'b, which extend through the rod 1 between the needles 5, 6 pass through the slits 10, 11 of the rod 2 and the eyelets 14', 15' of the rod 3, whilst the warp-yarns 'a go equally through the rod 1 between the needles, and across the eyelets 14, 15 of the rod 2 and the slits 10', 11' of the rod 3.

It suffices thus to displace the two latter rods in such a way that through the action of the curved slits 10, 11 and 10', 11' and through the transverse movement, made possible by the eyelets 14, 15 and 14', 15', the warp-yarns 'a, 'b are being displaced transversely by a small amount, in such a way that the straight displacement of the needles 5, 6 causes the third warp-yarn 'c to be alternately displaced from left to right of the first one, thus providing a centre-selvedge as shown in the Figures 8, 9 and 19 which differ one from the other only by the number of picks realized between two successive movements of the rod 1, that is of the needles 5, 6. These three rods 1, 2 and 3 are situated in a sheath 16, fixed behind the harness-frames 17. Each of these rods is actuated by a cable 18 passing on pulleys 19, 20, 21, 22 and moved by means of a cam device 23, capable to operate in due time the required traction for the displacement of said rod by a convenient small quantity. The warp-yarns 'a, 'b, 'c extend from a small special bobbin 24 which unrolls in the same manner as the weaver's beam.

It will be understood that, depending upon the lower branch or the upper branch of the curved slits 10, 11 which are placed opposite the eyelets 14', 15' the warp-yarns 'b will be situated at the left or at the right, i. e., they will be placed left or right with regard to the point of the needles 7, 8 and the latter will thus place the warp-yarn 'c at the right or the left of thread 'b. Similarly, the upper branch or the lower branch of the curved slits 10', 11' which are placed opposite the eyelets 14, 15, will place the warp-yarn 'a' at the left or at the right. The transverse movements of the warp-yarns 'a, 'b are thus definitely obtained by the straight alternative movement of the rods 2 and 3.

These movements could obviously be caused by all other means than those described previously. Similarly, said rods can be provided with other accessories.

What I claim is:

1. In a device for making the cutting portions of slit-up fabrics, the combination of three up and down movable rods, one rod carrying eye-needles and controlling the up and down movement of a first pair of warp yarns, one of the two other rods having means for controlling the up and down movement of a second pair of warp yarns and, simultaneously, the transverse movement of a third pair of warp yarns, the second one of said two other rods having means for controlling the transverse movement of the second pair of warp yarns and the up and down movement of the third pair of warp yarns, means for supporting said rods, and means for moving said rods up and down.

2. In a device for making the cutting portions of slit-up fabrics, the combination of three up and down movable rods, one rod carrying two downwardly pointing eye-needles and controlling the up and down movement of a first pair of warp yarns, which cross said rod at a horizontal slit formed therein above the eye-needles, said yarns turning around said needles before leading through the eyes, one of the two other rods having two small horizontal eyelets for imparting an up-and-down movement to a second pair of warp yarns and also having two vertical double-curved slits for controlling the transverse movement of a third pair of warp yarns, the second one of said two other rods having two small horizontal eyelets for imparting an up-and-down movement to the third pair of warp yarns, and two vertical double curved slits for controlling the transverse movement of the second pair of warp yarns, means for supporting said rods, and means for moving said rods up-and-down.

3. In a device for making the cutting portions of slit-up fabrics, the combination of three up and down movable rods, one rod carrying two downwardly pointing eye-needles and controlling the up and down movement of a first pair of warp yarns, which cross said rod at a horizontal slit formed therein above the eye-needles, said yarns turning around said needles before leading through the eyes, one of the two other rods having two small horizontal eyelets for imparting an up-and-down movement to a second pair of warp yarns, and two vertical double-curved slits for controlling the transverse movement of a third pair of warp yarns, the second one of said two other rods having two small horizontal eyelets for imparting an up-and-down movement to the third pair of warp yarns, and two vertical double-curved slits for controlling the transverse movement of the second pair of warp yarns so that the second and third pair of warp yarns are placed alternately on different sides of the needles, means for supporting said rods, and means for moving said rods up-and-down.

4. In a device for making the cutting portions of slit-up fabrics, the combination of three up-and-down movable rods, one rod carrying two downwardly pointing eye-needles and controlling the up-and-down movement of a first pair of warp yarns, which cross said rod at a horizontal slit formed therein above the eye-needles, said yarns turning around said needles before leading through the eyes, one of the two other rods having two small horizontal eyelets for imparting an up-and-down movement to the second pair of warp yarns, and two vertical double-curved slits for controlling the transverse movement of a third pair of warp yarns, the

second one of said two other rods having two small horizontal eyelets for imparting an up-and-down movement to a third pair of warp yarns, and two vertical double-curved slits for controlling the transverse movement of the second pair of warp yarns so that the second and third pair of warp yarns are placed alternately on different sides of the needles, said second and third rods also having two straight vertical slits causing the first pair of warp yarns to cross them freely during their up and down movement, means for supporting said rods, and means for moving said rods up-and-down. 10
